United States Patent Office

Des. 210,978
Patented May 7, 1968

210,978

ELECTRIC STAPLING MACHINE OR SIMILAR ARTICLE

Harry Preble, Jr., Cross River, N.Y., assignor to Swing-line Inc., Long Island City, N.Y., a corporation of New York

Filed Aug. 15, 1967, Ser. No. 8,273

Term of patent 14 years

(Cl. D54—14)

Des. 210,978

PAGE 2

FIG. 1 is an isometric view of an electric stapling machine or similar article showing my new design.

FIG. 2 is a side elevational view thereof.

FIG. 3 is a top plan view thereof.

FIG. 4 is a front elevational view thereof. The side of the design not shown is similar to the side disclosed.

I claim:

The ornamental design for an electric stapling machine or similar article, as shown and described.
